UNITED STATES - PATENT OFFICE.

CHARLES E. WILLIAMS, OF BROOKLYN, NEW YORK, ASSIGNOR TO AMERICAN CAN COMPANY, OF JERSEY CITY, NEW JERSEY, AND NEW YORK, N. Y., A CORPORATION OF NEW JERSEY.

SECURING SWIVEL-PLATES TO PERFORATED COVERS.

SPECIFICATION forming part of Letters Patent No. 695,424, dated March 11, 1902.

Application filed July 27, 1901. Serial No. 69,935. (No model.)

To all whom it may concern:

Be it known that I, CHARLES E. WILLIAMS, a citizen of the United States, and a resident of Brooklyn, in the county of Kings and State of New York, have invented certain new and useful Improvements in Securing Swivel-Plates to Perforated Covers, of which the following is a specification.

The object of my invention is to provide a means for securing a swivel-plate to a top or cap of a box adapted to discharge powders, condiment, and the like; and it consists, essentially, of having the perforated plate secured to the cover of the box by means of a stamped or drawn-up portion in the cover, which passes through an opening in the plate, and in afterward, by a die, or otherwise forcing down the edge of the drawn-up portion, so that it slightly overlaps the plate, thus serving as a rivet-head to hold the plate in place and also permit it to turn on said drawn-up portion, as will now be set forth in detail.

In the accompanying drawings, Figure 1 is a central vertical section of a box cover or top, showing a central drawn-up portion; Fig. 2, a central vertical section showing the perforated plate secured to the top; Fig. 3, a top view of the cover; and Fig. 4, an enlarged cross-section of portion of the cover and perforated swivel-plate, showing the manner in which the drawn-up portion holds the plate in position.

Ordinarily the swivel-plate 5 is held to the top or cover 6 by means of a rivet, and it is found in practice that the cost of assembling and placing the rivet in position is the costly part of making these perforated tops. To cheapen the cost, therefore, I draw out a portion centrally, as shown at 7, the diameter of

this drawn-up portion depending, of course, on the size of the cover. A hole is made centrally in the perforated plate 5, so that it will permit the drawn-up portion 7 to pass through, after which the top is put under a press and the drawn-up portion forced down, so that the edge bulges outwardly, as shown at 8, thus slightly overlapping the plate 5 and holding it in position. When thus constructed, the plate 5, which is provided with registering perforations, can be turned the same as though riveted in the usual way, so that the perforation 9 will coincide with similar perforations in the cover 6 or be closed, as may be desired, by the turning of the plate.

It is obvious that the extent of the pressure on the drawn-up portion determines the degree of tightness between the plate and cover, and it will be readily understood that this method of securing together adjacent plates is a very simple and efficient one, instead of using rivets, as the plate can be firmly fixed instead of loosely, as herein shown.

What I claim is—

A cover for condiment-boxes, having centrally a solid, drawn-up portion, a plate or disk with a central aperture in which the drawn-up portion rests, said drawn-up portion having its edges crimped, or compressed downwardly, to slightly overlap and hold the apertured disk, said cover and disk having registering perforations as set forth.

Signed at Brooklyn, in the county of Kings and State of New York.

CHAS. E. WILLIAMS.
